Application April 14, 1951, Serial No. 221,009

28 Claims. (Cl. 30—9)

1

The present invention relates in general to can openers, and more particularly to can openers of the type utilizing a cutting wheel for removing the top of the can together with a feed wheel or gear for rotating and driving the can relative to the cutting wheel during such removal. The present invention is an improvement on the can opener shown in my co-pending patent application Serial No. 129,139, filed November 23, 1949, now Patent No. 2,602,991.

As disclosed in my co-pending patent application referred to above, one form of can opener may provide a mechanism by which the feed wheel and cutting wheel are automatically advanced or retracted relative to each other to grip and puncture a can or to release the can depending upon the initial direction of rotation of the can opener operating handle.

It is an important object of my present invention to provide an improved form of can opener of the type referred to above and having means to facilitate the initial can gripping and puncturing operation to thus reduce the effort expended in operating the can opener.

In the preferred embodiment of my present invention, the rotary operating handle and associated operating mechanism are provided with an arrangement of clutch and gearing by means of which the cutting wheel is positively rotated for all rotary movements of the handle and including the period of time during which the feed wheel and cutting wheel are moved relative to each other to initially grip and puncture the can. Thus, the initial step of puncturing the can body is greatly facilitated since the cutting wheel engages the can with a combined rotary and linear puncturing movement.

Another object of my present invention is to provide an improved form of can opener of the general type referred to above and having a modified operating mechanism by means of which the continued rotation of the operating handle in the selected direction to open the can is facilitated and obtained with a minimum of disturbing effects and noises.

A further object of my present invention is to provide a can opener of the type referred to and having simplified construction facilitating the initial assembly of the can opener and providing for automatic adjustment of the cutting wheel and feed gear in response to variations or irregularities of the can seam encountered as the can is rotated and opened.

Yet another object of my invention is to provide an improved form of can opener of the class

2

described and having means to initially adjust the normal minimum spacing between the inner face of the cutting wheel and the outer face of the feed wheel to thus facilitate the assembly of a can opener to the required manufacturing tolerances.

Still a further object of the invention is to provide a can opener having an improved form of can rest or shoulder for holding the can in pressure engagement with the can advancing wheel.

Other objects and advantages of my invention will be apparent with reference to the following specification and drawings in which:

15 Fig. 1 is a side elevation of the can opener of my present invention as seen from the operating handle side, and with the parts in the can receiving position;

20 Fig. 2 is a fragmentary side elevation of the operating end of the can opener as seen from the opposite side to that of Fig. 1;

25 Fig. 3 is an end elevation of the operating end of the can opener with parts in position of Figs. 1 and 2 and partially in section to show further detail;

30 Fig. 4 is a section on the line 4—4 of Fig. 2 in the direction of the arrows;

Fig. 5 is a section on the line 5—5 of Fig. 1 in the direction of the arrows;

35 Fig. 6 is a section on the line 6—6 of Fig. 2 in the direction of the arrows;

Fig. 7 is a view similar to Fig. 1 but showing the parts in the position assumed after puncturing and while gripping a can for rotary cutting;

40 Fig. 8 is a view similar to Fig. 2 but showing the parts in the position of Fig. 7;

Fig. 9 is an end view of the operating end of a can opener with the parts including the cutting wheel and feed wheel in the position shown in Figs. 7 and 8; and

45 Fig. 10 is an exploded perspective assembly view to show all of the operating parts of the can opener in their relative positions of assembly.

Referring to the drawings, the numeral 10 identifies the main body of the can opener, the rear end 11 of which may be attached to a supporting wall surface in any suitable fashion. The operating end of the can opener main body 10 as shown in Figures 2, 3, 4 and 8 through 10 of the drawings is provided with an embossed portion 12 for supporting the inclined spindle 13 on which the cutting wheel 14 is rotatably journaled. The cutting wheel 14 may be secured on the spindle 13 by means of the lock nut 15

as particularly shown in Fig. 4 of the drawings. In this connection it will be noted that the cutter wheel 14 is provided with a shank portion 16 on which are splined a pair of driving gears 17 and 18 and the entire assembly is held in the 5 desired axial relation on the spindle 13 by means of a coiled compression spring 19. It should now be evident that the cutter wheel 14 is rotatably mounted on the can opener main body 10 in a desired fixed axial position.

The feed wheel, operating handle and associated cam and eccentric driving mechanism, to be later described in detail, are all mounted on the subassembly plate 20. The plate 20 is preferably of thin resilient material such as spring metal and is fastened to the main body 10 at two spaced points 21 and 22 respectively. The subassembly plate 20 may be secured at 21 and 22 in any suitable fashion such as by rivets or the like, but in the embodiment of the invention, as shown in Figs. 2 and 3, bolts 23 and 24 together with cup-shaped spring washers 25 and 26 may be used. Since the bolts 23 and 24, as shown in Fig. 3 of the drawings, are not threaded to the main body member 10, it should be apparent that a limited separational movement between the subassembly plate 20 and the main body 10 is permitted. When, in the alternative, the subassembly 20 is riveted to the main body 10, as previously mentioned, a limited separational movement between the main body 10 and subassembly plate 20 may still take place due to the inherent springiness of the metal plate 20 which, as pointed out, is only secured to the main body 10 at the two spaced points 21 and 22. Thus the spacing between the inner face of the cutting wheel 14 and the outer face of the feed wheel 30, which is carried by the subassembly plate 20 in a manner to be further described in detail, may be automatically varied within limits by the separational movement of the body 10 and subassembly plate 20 as the can opener is used.

To initially determine or adjust the minimum spacing between the rear face of the cutting wheel 14 and the front face of the feed wheel 30 at the time of assembly of the can opener, a set screw 27 and lock nut 28 may be secured to the main body 10 as shown in Figs. 2 and 6 of the drawings. By threading the set screw 27 into and through the body 10, the end of the set screw 45 may be caused to abut the unperforated wall of the subassembly plate 20 to force the subassembly plate 20 and main body 10 to separate by a minimum amount determined by the threaded position of the set screw.

The feed wheel 30 is secured to the shaft 31 of the operating handle 32 and at the time of assembly is threaded at 33 on the shaft 31 and thereafter may be keyed to the shaft if desired by peening the protruding end of the threads 33 on the shaft 31. As most clearly shown in Figs. 4 and 10 of the drawings, the shaft 31 is rotatably journaled in the bore 34 of the rotatable plug member 35 having a circular shoulder portion 36 rotatably journaled in the bore 37 of the subassembly plate 20. The plug member 35 is provided with a shank portion 38 which extends through the opening 39 of the cam plate 40. The cam plate 40 also has a circular shoulder portion 41 which is adapted to be journaled in the opening 37 to abut the shoulder portion 36 of the plug member 35 when the can opener is assembled. The cam plate 40 and plug member 35 are connected to turn together as a unit in any suitable fashion, such as the projection

10 of pin 42 into the opening 43 so that rotation of the cam plate 40 causes a corresponding rotation of the plug member 35. It should also be noted that the bores 34 and 39 are eccentrically located with reference to the circular shoulders 36 and 41 and the bore 37 so that a rotation of the plug 35 and cam plate 40 causes the shaft 31 and feed wheel 30 to advance or retract with relation to the cutter wheel depending upon the relative eccentric positions of the members referred to.

Now with further reference to Figs. 2, 8 and 10 of the drawings, it will be noted that a peripheral portion of the plug member 35 is provided with gear teeth 45 adapted to mesh with the cutter wheel driving spur gear 18 during the rotary movement of the plug member to advance or retract the feed wheel and cutter wheel relative to each other. Thus the cutter wheel 14 is positively rotated during the initial step of gripping and puncturing the can.

In order that continued rotation of the cutter wheel 14 and driving gears 17 and 18 may be had to open the can after the cutting wheel and feed wheel are brought together and after the rotation of the plug member 35 has been stopped in the position shown in Figs. 7 and 8 (wherein it will be noted that the shoulder 50 of the cam plate 40 is adjacent the stop pin or lug 51 on the subassembly plate 20), a portion of the gear teeth 45 are removed at 46 to thus automatically disengage gear 18 from the plug 35. However, spur gear 47 which is keyed by the flat 48 to the shoulder 49 of the shaft 31 continues to rotate with the rotational movement of the operating handle 32 and engages with gear 17 of the cutter wheel 14 when the parts of the can opener are in the position shown in Figs. 8 and 9 with the feed wheel 30 and cutting wheel 14 brought together. It should thus be apparent that the cutting wheel 14 is rotated either by the gear teeth 45 of the rotatable plug engaging with the spur gear 18 or by the spur gear 47 engaging with the spur gear 17.

To cause a rotation of cam plate 40 and plug 45 35 in either direction during a portion of a corresponding rotation of the handle 32 in either direction, a rotation responsive clutch device is provided. The cam plate 40 is formed with a slot portion 52 in its periphery. A spring pressed lever 53 (see Fig. 5) is pivoted at 54 on the operating handle 32 and its edge portion 55 may engage in the slot 52 during a selected period of angular movement of the handle 32 as will be further described. The subassembly plate 20 is provided with a raised cam portion 56 with which the lever 53 engages as the handle 32 is rotated thus to lift the edge portion 55 of the lever against the tension of spring 57 out of engagement with slot 52. The hub of the crank handle is provided with a welded on inner plate 58 carrying the shaft 31 and this has a portion containing a slot 59 which forms a guideway for the inner end of lever 53.

Interposed between the face of cam plate 40 and the inner plate 58 of the crank handle is a lost motion silencer disk 60 notched inwardly from one edge and having adjacent the notch an upstanding lug 62 extending into an aperture 63 in the plate 58; the latter aperture is sufficiently larger than lug 62 to permit the lug to shift circumferentially a small amount in either direction relative to the crank hub.

Now, assuming the can opener parts to be 70 75 in the position shown in Figs. 1 to 4 with ro-

tation of the handle in a counter-clockwise direction prevented by reason of engagement of the stop pin 51 with the shoulder 64 of the cam plate 40 and the engagement of the handle lever 53 in the slot 52 of the cam plate, the cutting wheel 14 and the feed wheel 30 are in spaced apart position to permit insertion of a can flange therebetween. Upon rotation of the handle 32 in a clockwise direction (Fig. 1) the cam plate and the plug 35 are similarly rotated by reason of the engagement of the handle lever 53 in cam slot 52; also, the leading face of lever 53 bears against the edge 61 of the notch in the silencer disk causing it to turn with the handle. Clockwise rotation of the handle, cam plate 40, plug 35, and the silencer disk 60 continues during approximately 180° of angular rotation, in which time the feed wheel 30 is moved from the position shown in Figs. 2 and 3 to the position shown in Figs. 8 and 9, causing the cutter wheel to puncture the lid of the can and causing the flange of the can to be gripped between the feed wheel and cutter wheel. It is important to note that during this first interval of movement, the cutter wheel is rotated due to the meshing of gear teeth 45 on the plug 35 with the teeth of spur gear 18; positive rotation of the cutter wheel during this interval materially reduces the resistance of the lid to puncturing and correspondingly reduces the amount of force the operator must apply to the handle 32 in order to effect the initial penetration of the lid by the cutter wheel.

At the end of the first 180° of angular clockwise movement, the handle lever 53 rides up on the cam 56 to lift the edge portion 55 of the lever out of slot 52 of the cam plate 40. With the lifting of lever 53 above the level of the silencer disk at this point, rotation of the disk halts momentarily and as the clockwise rotation of handle 32 continues, lever 53 now passes over the edge 61 of the disk to a position adjacent the notch therein. As previously indicated, the loss of motion between the silencer disk and the handle is limited to the amount of movement lug 62 enjoys in aperture 63, and accordingly, as soon as the lever 53 advances past the notch in the silencer disk, the latter resumes rotation and thereafter continues to turn with the handle. During the ensuing clockwise rotation of the handle, lever 53 continues to rest on the surface of the silencer disk, and once in each revolution of the handle passes the slot 52 in cam plate 40 without dropping thereinto.

The continued clockwise rotation of the handle of course also causes a rotation of feed wheel 30, spur gear 47, and cutting wheel 14 to advance the can relative to the cutter wheel and sever the lid thereof; the fact that silencer disk 60 prevents the edge portion 55 of lever 53 from dropping into slot 52 or engaging the cam surface 56 during the severing of the lid, eliminates the annoying clicks and noises which otherwise would occur but for the silencer disk. It also should be borne in mind that after the first 180° of clockwise rotation of the handle from its starting position, the untoothed portion 46 of the plug 35 is opposite gear 18 thus disengaging the geared connection between the cutting wheel and the plug 35 for the continued clockwise rotation of the handle 32 while plug 35 and cam plate 40 remain stationary in the position indicated in Fig. 8.

During the can opening operation the side wall of the can rides against the end of a lug

70 projecting laterally from the main body plate 10 which serves to maintain the side of the can substantially vertical. Also in order to hold the bead or flange of the can in firm pressure engagement with the feed wheel 30, the can is urged downwardly by a spring loaded can rest, the construction of which may best be appreciated from Figs. 2 and 6. Referring to the latter figure, it will be seen that the can rest comprises a pair of arms 72 and 73 extending loosely through slots 74 in an offset portion of the main body plate 10. Between the arms is a coiled compression spring 75 urging them apart; the arms are bent to form exterior shoulders 76 and interior shoulders 77 which prevent them from moving farther apart than shown under the influence of the spring, but these shoulders will not prevent the arms from moving toward one another and compressing the spring. Thus, 10 when the upper edge of the can abuts the lower arm 73 and lifts it slightly, as it does when the can is lifted to lid severing position, spring 75 maintains a downward force on the can to hold the flange or bead in tight pressure engagement with the serrated feed wheel 30 to facilitate advancing of the can relative to the cutter wheel. It should be understood that the plug member 35 is rotatable and axially slidable through the bore or opening 80 of the main body member 10 so that with a separational movement of the main body member 10 and the subassembly plate 20, as previously described, the outer face of the feed gear 30 will move away from the inner face of cutting wheel 14. Normally these two faces are close together as indicated in Fig. 9, but when, in the course of opening a can, the vertical seam in the side wall thereof passes between the two faces it induces the aforementioned separational movement which allows the necessary "give" to permit the can seam to pass between the cutter wheel and the feed wheel without imposing any undue strain on the parts. Also, as previously indicated, the minimum spacing between the two faces may readily be adjusted by means of the set screw 27 and lock washer 28.

To release the opened can, the handle 32 is merely rotated in the counter-clockwise direction. Referring to Fig. 7, the lost motion silencer disk 60 remains stationary for a brief interval at the beginning of such rotation of the crank handle so that lever 53 passes over the edge 61 into the notch of the silencer disk and rests on the face of cam plate 40; as soon as it passes over edge 61, the trailing edge of aperture 63 in the hub plate 58 (see Fig. 10) engages lug 62 and thus causes the lost motion disk 60 to begin turning with the crank. When the crank turns through approximately 180° counter-clockwise from the position shown in Fig. 7, lever 53 drops into notch 52 and causes the cam plate 40 and plug 35 then to turn with the crank through the ensuing 180° or until shoulder 64 engages stop pin 51. The parts now are back in the position illustrated by Figs. 1 to 4, from which it will be noted that the feed gear 30 is drawn downwardly from the cutter wheel so that the can flange may be withdrawn from between the two. The coiled compression spring 82 encircling the crank shaft 31 between the silencer disk and the crank hub plate 58 urges the cam plate 40 against the face of the subassembly plate 20 with sufficient force that the friction between the two will prevent free rotation of the cam plate 40; since the lever 53 is in notch 52 of the cam plate, this resistance

to free rotation of the latter will hold the crank in the position shown in Fig. 1 until it is manually turned in a clockwise direction by the operator incident to inserting another can in the can opener for the purpose of severing the lid thereof.

From the foregoing it will be seen that this invention is one well adapted to attain all of the ends and objects hereinbefore set forth together with other advantages which are obvious and which are inherent to the apparatus.

It will be understood that certain features and subcombinations are of utility and may be employed without reference to other features and subcombinations. This is contemplated by and is within the scope of the claims.

Inasmuch as many possible embodiments of the invention may be made without departing from the scope thereof, it is to be understood that all matter herein set forth or shown in the accompanying drawings is to be interpreted as illustrative and not in a limiting sense.

I claim:

1. A can opener comprising a body member, a rotatable cutting wheel carried by said body, a rotatable feed wheel, means to move said feed wheel towards said cutting wheel to grip and puncture a can, and gear means meshed throughout the movement of said feed wheel towards said cutting wheel for rotating both wheels during said movement.

2. A can opener comprising a body member, a cutting wheel rotatably mounted on said member, an operating handle rotatably mounted on said member, a feed wheel connected for rotation with said handle, means associated with said handle during a first rotational movement thereof in a selected direction to move said feed wheel towards said cutting wheel, said first means also connecting said cutting wheel to be rotated by said handle during said first rotational movement, and second means connecting said cutting wheel to said feed wheel to be rotated by continued rotation of said handle in the selected direction.

3. A can opener comprising a body member, a cutting wheel rotatably secured to said body member, a plug member rotatably mounted in a bore of said body member, a bore extending through said plug member and eccentrically positioned with respect to the bore of said body member, a rotatable operating handle having a spindle extending through said second bore, a feed wheel secured to said spindle to be rotated with said handle, first gear means connecting said plug member to said cutting wheel during the rotation of said plug to rotate said cutting wheel, clutch means connecting said handle to said plug to rotate said plug during a first portion of the rotation of said handle in a selected direction whereby the spindle and feed wheel are moved towards said cutting wheel, means to disconnect said clutch means during continued rotation of said handle in the selected direction, and second gear means connecting said feed wheel and said cutting wheel for rotation therewith after said clutch means is disconnected.

4. A can opener comprising a body member, a cutting wheel rotatably secured to said body member, a plug member rotatably mounted in a bore of said body member, a bore extending through said plug member and eccentrically positioned with respect to the bore of said body member, a rotatable operating handle having a spindle extending through said second bore, a feed

wheel secured to said spindle to be rotated with said handle, first gear means connecting said plug member to said cutting wheel during the rotation of said plug to rotate said cutting wheel, clutch means connecting said handle to said plug to rotate said plug during a first portion of the rotation of said handle in a selected direction whereby the spindle and feed wheel are moved towards said cutting wheel, means to disconnect said clutch means during continued rotation of said handle in the selected direction, and second gear means connecting said feed wheel and said cutting wheel for rotation therewith after said clutch means is disconnected.

5. The invention of claim 4 in which said clutch means comprises a cam plate secured to said plug for rotation therewith and having a notch on its peripheral edge, a spring pressed lever carried by said handle and normally engaging said notch, and cam means on said body to engage said lever and disengage the lever from the notch of said cam plate as the rotation of said handle is continued in the selected direction after a predetermined amount of rotation.

6. The invention of claim 5 in which means is provided to hold said lever out of engagement with said notch and said cam means during the continued rotation of said handle in the selected direction.

7. A can opener comprising a body member, a cutting wheel rotatably secured to said body member, a subassembly plate fastened to said body member, a plug member rotatably and slidably mounted in a bore of said body member and non-slidably journaled in a bore of said subassembly plate to be rotatably carried thereby, a bore extending through said plug member and eccentrically positioned with respect to the bore of said body member, a rotatable operating handle having a spindle extending through said second bore, a feed wheel secured to said spindle to be rotated with said handle, first gear means connecting said plug member to said cutting wheel during the rotation of said plug to rotate said cutting wheel, clutch means connecting said handle to said plug to rotate said plug during a first portion of the rotation of said handle in a selected direction whereby the spindle and feed wheel are moved towards said cutting wheel, means to disconnect said clutch means during continued rotation of said handle in the selected direction, and second gear means connecting said feed wheel and said cutting wheel for rotation therewith after said clutch means is disconnected.

8. A can opener comprising a body member, a cutting wheel rotatably secured to said body member, a subassembly plate resiliently fastened to said body member for limited separational movement therebetween, a plug member rotatably and slidably mounted in a bore of said body member and non-slidably journaled in a bore of said subassembly plate to be rotatably carried thereby, a bore extending through said plug member and eccentrically positioned with respect to the bore of said body member, a rotatable operating handle having a spindle extending through said second bore, a feed wheel secured to said spindle to be rotated with said handle, first gear means connecting said plug member to said cutting wheel during the rotation of said plug to rotate

said cutting wheel, clutch means connecting said handle to said plug to rotate said plug during a first portion of the rotation of said handle in a selected direction whereby the spindle and feed wheel are moved towards said cutting wheel, means to disconnect said clutch means during continued rotation of said handle in the selected direction, and second gear means connecting said feed wheel and said cutting wheel for rotation therewith after said clutch means is disconnected.

9. A can opener comprising a body member, a cutting wheel rotatably secured to said body member, a subassembly plate resiliently fastened to said body member for limited separational movement therebetween, means to adjustably limit the minimum separation between said plate and said body member, a plug member rotatably and slidably mounted in a bore of said body member and non-slidably journaled in a bore of said subassembly plate to be rotatably carried thereby, a bore extending through said plug member and eccentrically positioned with respect to the bore of said body member, a rotatable operating handle having a spindle extending through said second bore, a feed wheel secured to said spindle to be rotated with said handle, first gear means connecting said plug member to said cutting wheel during the rotation of said plug to rotate said cutting wheel, clutch means connecting said handle to said plug to rotate said plug during a first portion of the rotation of said handle in a selected direction whereby the spindle and feed wheel are moved towards said cutting wheel, means to disconnect said clutch means during continued rotation of said handle in the selected direction, and second gear means connecting said feed wheel and said cutting wheel for rotation therewith after said clutch means is disconnected.

10. The invention of claim 8 in which said clutch means comprises a cam plate secured to said plug for rotation therewith and having a notch on its peripheral edge, a spring pressed lever carried by said handle and normally engaging said notch, and cam means on said body to engage said lever and disengage the lever from the notch of said cam plate as the rotation of said handle is continued in the selected direction after a predetermined amount of rotation.

11. The invention of claim 10 in which means is provided to hold said lever out of engagement with said notch and said cam means during the continued rotation of said handle in the selected direction.

12. The invention of claim 9 in which said clutch means comprises a cam plate secured to said plug for rotation therewith and having a notch on its peripheral edge, a spring pressed lever carried by said handle and normally engaging said notch, and cam means to engage said lever and disengage the lever from the notch of said cam plate as the rotation of said handle is continued in the selected direction after a predetermined amount of rotation.

13. The invention of claim 12 in which means is provided to hold said lever out of engagement with said notch and said cam means during the continued rotation of said handle in the selected direction.

14. In a can opener of the type having a cutter wheel and a cooperating feed wheel to engage the can, a frame, a rotary member mounted on said frame for limited rotation in opposite directions about a fixed axis, a driving shaft eccentrically mounted on said rotary member for orbital movement about said fixed axis and for

independent rotary movement about its own axis, one of said wheels mounted on said frame and the other mounted on said shaft for movement toward and away from said one wheel upon said orbital movement of the shaft, a crank member connected to the shaft for turning same, a positive clutch for causing said rotary member to turn with said crank member during a predetermined partial rotation of the latter, said clutch including a dog carried by one of the members, a notch in the other member for receiving the dog thereby to couple the two members together, a spring urging said dog toward the notch, cam means on the frame positioned to engage the dog and move same out of the notch after said predetermined partial rotation of the crank member, whereby continued rotation of the crank member only turns said shaft about its own axis without causing further rotation of said rotary member, and a barrier shiftable between the dog and the notch when the dog is moved out of the notch, for preventing the dog from moving back into the notch as it passes thereover during said continued rotation of the crank member.

15. A can opener as in claim 14 having means for shifting said barrier upon reversal of the direction of rotation of the crank member after said continued rotation, thereby to permit said dog to move back into said notch.

16. In a can opener of the type having a cutter wheel and a cooperating feed wheel to engage the can, a frame, a rotary member mounted on said frame for limited rotation in opposite directions about a fixed axis, a driving shaft eccentrically mounted on said rotary member for orbital movement about said fixed axis and for independent rotary movement about its own axis, one of said wheels mounted on said frame and the other mounted on said shaft for movement toward and away from said one wheel upon said orbital movement of the shaft, a crank member connected to the shaft for turning same, a positive clutch for causing said rotary member to turn with said crank member during a predetermined partial rotation of the latter, said clutch including a dog carried by one of the members, a notch in the other member for receiving the dog thereby to couple the two members together, a spring urging said dog toward the notch, a silencer disk interposed between said members and rotatable independently of said members about the axis of said shaft, said disk having an aperture through which said dog projects into said notch whereby said disk turns with said members when they are thus coupled by said clutch, cam means on the frame positioned to engage said dog and lift same out of said notch and aperture after said predetermined partial rotation of the crank member whereby continued rotation of the crank member turns said shaft about its own axis without causing further rotation of said rotary member, said disk being effective to halt momentarily when said dog is lifted out of said aperture, and a lost motion

connection between said disk and crank member for thereafter causing said disk to resume and continue rotation with the crank member, the loss of motion of said disk due to said momentary halting thereof being sufficient to shift said aperture out of register with said dog whereby the dog cannot drop back into said notch as it passes thereover during said continued rotation of the crank member.

17. In a can opener of the type having a cutter wheel and a cooperating feed wheel, a body plate

11

carrying said wheels, a can rest assembly for forcibly urging the rim of a can against the feed wheel during the can opening operation, said assembly comprising a pair of laterally spaced arms extending outwardly from one side of said body plate in a direction substantially normal thereto, each of said arms having a portion extending through a slightly enlarged aperture in the body plate whereby said portion is loose in the aperture, shoulders on the respective arms engaging opposite faces of said plate adjacent said apertures to prevent the outer ends of the arms from moving apart beyond a predetermined distance but permitting same to move toward one another, a spring between said arms urging the outer ends thereof apart, one of said arms comprising a can rest adapted to be engaged by the rim of a can and urged thereby toward the other arm during the can opening operation.

18. A can opener as in claim 17 wherein said shoulders comprise a first pair of shoulders on the respective arms and a second pair of shoulders on the respective arms, the shoulders of said first pair being disposed on said one side of said plate and extending away from one another, and the shoulders of said second pair being disposed on the opposite side of the plate and extending toward one another.

19. In a can opener of the type having a rotary cutting wheel and a cooperating feed wheel, a main body member, a stationary plate fixedly secured to said body member at two spaced points thereon thereby to prevent shifting of said plate in its own plane, one of said wheels being rotatably mounted on the body member and the other being rotatably mounted on said plate intermediate said two points, and said plate being formed of resilient sheet material thereby to permit limited movement of said other wheel in a direction normal to the plane of said plate due to bowing of the plate between said two points.

20. In a can opener of the type having a rotary cutting wheel and a cooperating feed wheel, a main body member, a stationary plate member fixedly secured to the body member at two spaced points thereon, thereby to prevent shifting of said plate member in its own plane, said plate member being formed of resilient sheet material thereby to permit limited bowing of the plate member between said two points, one of said wheels being rotatably mounted on the plate member intermediate said two points with its axis generally transverse to the plane of the plate, the other wheel being rotatably mounted on said body member with its axis aligned in the general direction of said first axis whereby the axial distance between said wheels varies in accordance with the bowing of said plate member.

21. A can opener as in claim 20, wherein one of said members contains an aperture and the wheel mounted on the other one of said mem-

bers is carried on the free end of a spindle which projects through said aperture from said other member.

22. A can opener as in claim 20, wherein one of said members carries a thrust element bearing against the other member between said two points, said element being adjustable to vary the amount of bowing of said plate member.

23. A can opener as in claim 20, wherein one of said members has intermediate said two points a threaded aperture in which is received a screw whose axis is normal to the plane of said plate and whose end abuts the other end of said members, whereby rotation of said screw is effective to vary the amount of bowing of said plate member.

24. A can opener as in claim 23, having means for locking said screw against rotation relative to said one member.

25. In a can opener of the type having a rotary cutting wheel and a cooperating feed wheel, a main body member having a flat face, a subassembly plate member parallel to and adjacent said face of the body member, said plate member being secured to the body member at a plurality of spaced points thereby to prevent movement of the plate member in its own plane, spring means at each of said points clamping said plate and body members together but yieldable to permit limited separational movement between the two, one of said wheels being rotatably mounted on the body member and the other being rotatably mounted on the plate member to move therewith upon said separational movement.

26. A can opener as in claim 25, having a stop carried by one of said members and normally abutting the other member under the influence of said spring means thereby to limit the minimum separation of the two members, and means for adjusting said stop relative to said one member to vary said minimum separation.

27. A can opener as in claim 25, wherein one of said members has a threaded aperture in which is received a screw whose axis is normal to said face and whose end abuts the other member, whereby rotation of said screw adjusts the minimum separation between the two members.

28. A can opener as in claim 27, having means for locking said screw against rotation relative to said one member.

WILLIAM J. LANDRY.
